UNITED STATES PATENT OFFICE.

LOUIS ALTHOF, OF HOBOKEN, NEW JERSEY, AND HERMANN THOMASS,
OF BROOKLYN, NEW YORK.

DESIGN FOR A TOY WAGON.

Specification forming part of Design No. 7,436, dated May 19, 1874; application filed February 20, 1874.
[Term of Patent 7 years.]

To all whom it may concern:

Be it known that we, LOUIS ALTHOF, of Hoboken, in the county of Hudson and State of New Jersey, and HERMANN THOMASS, of Brooklyn, in the county of Kings and State of New York, have invented a Design for a Toy Wagon, of which the following is a specification:

Figure 1 is a side view of our new design for a toy wagon, and Fig. 2 is a top view of the front portion of the same.

Similar letters of reference indicate corresponding parts in both figures.

The nature of my design is fully represented in the accompanying drawings, to which reference is made.

A and C represent the front of the wagon. B B are oval drums attached to the front axle, made of metal or other suitable material. D

is a figure, attached to the side of the wagon between the front and rear wheels, having the appearance of walking as the wagon moves. One of these figures is placed on each side of the wagon. E is a figure standing over the rear axle.

Having thus described my invention, what I claim is—

1. The design for a toy wagon formed by the running parts having the figures D and E thereon, substantially as described and shown.

2. The design for a toy wagon formed by the figures D E and drums B B, substantially as described and shown.

LOUIS ALTHOF.
HERMANN THOMASS.
